UNITED STATES PATENT OFFICE.

DAVID E. SKEDGELL, OF MILLVILLE, NEW JERSEY, ASSIGNOR TO MILLVILLE MANUFACTURING COMPANY, OF MILLVILLE, NEW JERSEY, A CORPORATION OF NEW JERSEY.

FILLING STOP MOTION FOR LOOMS.

Application filed October 17, 1925. Serial No. 62,386.

This invention relates to stop motions employed in connection with looms to automatically effect stoppage in the absence of the filling due to breakage, or to exhaustion of the bobbin in the shuttle. Such a device embodies a detector in the form of a pivoted fork, which, so long as it is engaged by the filling thread of each beat of the lay under normal operating conditions of the loom, permits the weaving to proceed, but which when not so engaged, as in the absence of the filling, automatically causes the belt shipper to be tripped to immediately stop the loom. Now obviously with devices of this kind as ordinarily constructed, abnormal obstructions, for example, an accumulation of lint (customarily referred to as "fly") would act in the same way on the detector and prevent stoppage of the loom, notwithstanding absence of the filling thread.

It is toward overcoming the contingency just referred to, that the present improvement is directed. In other words, the object of my invention is to provide means capable of causing automatic stoppage of the loom in the presence of any abnormal obstruction likely to interfere with proper functioning of the detector, and thereby prevent the loom from continuing in operation with broken filling, or an empty shuttle and causing imperfections such as thin places in the weave.

With reference to the drawings, Fig. I is a partial plan view of a loom conveniently embodying the filling stop motion of my invention; and

Fig. II is a fragmentary detail section taken as indicated by the arrows II-II in Fig. I.

For convenience of illustration, I have herein shown my invention as applied to an automatic loom of the "Northrop" type, whereof the lay is comprehensively indicated at 10, and the breast beam with its appendages at 11. Secured to the breast beam 11 at one end thereof, is a lateral guide 12 for a slide 13 which remains stationary in the position of Figs. I and II during normal operation of the loom. At its outer end the slide 13 has operative connection with the belt shipper tripping mechanism—that is to say, engages a tripping finger 14 that is pivoted at 15 and reaches over to the belt shipper arm 16, (or clutch arm as the case may be), the latter being

normally held locked in active position against the action of a spring (not shown), by a lateral notch 17 of a motion-limiting slot 18, provided in an extension 19 of the breast beam 11. At its inner end, the slide 13 pivotally supports a detector 20 having the form of a fork with depending prongs 21, and a laterally-extending yoke-like tail piece 22. This detector 20 cooperates in a well known manner with a grid 23 set on the lay 10 in an interval between the reed 24 and the shuttle box 25, as shown in Fig. I.

The motion for actuating the belt shipper tripping mechanism is derived from an actuator 26 that is continuously vibrated or oscillated by a suitable cam on the cam shaft (not shown) of the loom in the customary manner. The upper end of this actuator 26 projects into a longitudinal opening in the slide 13 to impart reciprocatory movement 75 to a pivotally attached member 27 that rests on a web 28 extending transversely across the bottom of the slide opening. As shown in Fig. II, the member 27, instead of being a single hook as is the usual case with stop motions of the Northrop type, comprises two hook-like arms 29, 30, whereof the former is straight and horizontal, while the latter is curved to overhang the first mentioned one and separated from it by an intervening 80 bight 31. The arms 29, 30, furthermore, are respectively recessed as at 32, 33, thereby affording notches in different planes for engaging with the yoke-like tail 22 of the detector 20, as hereinafter fully explained. 85

The operation of my filling detector is as follows: Assuming the loom to be in normal operation and the actuator 26 constantly vibrating to reciprocate the member 27 relative to the slide 13, it will be apparent upon 95 the forward motion of the lay 10 with filling lying across the grid 23, that the detector 20 will be swung to the full line position of Fig. II to maintain the tail piece 22 above the level of the recess 32 in the lower or horizontal arm 29 of the hooked member 27. In the absence of the filling, however, the detector 20 will not be affected as above noted, with the consequence that its tail piece 22 will be engaged in the notch 105 32 of the lower arm 29 of member 27, as shown in dotted lines in Fig. II, and, as said member moves forward, the slide 13 will be obliged to follow. Such movement of the slide 13 is thereupon imparted directly to 110

the tripper arm 14, thereby causing the belt shipper 16 to be displaced from locking engagement with the notch 17 and released to action of its spring for immediate stoppage 5 of the loom. In the event of the presence of a more bulky obstruction than the filling before the grid 23, such for example, as an accumulation of lint or "fly," the detector 20 upon approach of the lay 10, will obviously be swung to a greater degree than before and its tail piece 22 lifted to the plane of the upper hook arm 30 of the member 27 as shown in dot-and-dash lines in Fig. II, and thus engaged by the notch 33 with a result that the loom is stopped through the same interposed instrumentalities and in precisely the same manner as previously explained.

By my invention, I have thus provided for 20 automatic stoppage of the loom not only in the absence of the filling before the grid, but, also in the presence of abnormal obstructions of the character referred to, which, with stop motions as usually designed, 25 would influence the detector to keep the loom running notwithstanding absence of the filling.

It is to be particularly observed that my invention necessitates no change whatever 30 either in the construction of a typical Northrop loom or in its stop motion except for the substitution of a very simple element, namely the double hook member 27 in place of the characteristic single hook usually provided; nor will it interfere in any way with the operation of the filling replenishing mechanism with which such looms are usually equipped.

Having thus described my invention, I 40 claim:

1. A filling stop motion for looms, comprising a normally stationary slide operatively connected to the belt shipper tripping mechanism, a filling detector having 45 depending prongs and a lateral tail piece carried by the slide, and a member embodying superposed hook arms moving constantly relative to the slide during operation of the loom, said hook arms being respectively 50 capable of engaging the detector tail piece at different levels incidental to positioning of the latter occasioned by absence of the filling, or by presence of abnormal obstructions other than the filling to effect automatic 55 stoppage of the loom.

2. A filling stop motion for looms, comprising a normally stationary slide operatively connected to the belt shipper tripping mechanism, a filling detector having depending prongs and a lateral tail piece carried by 60 the slide, and a member embodying superposed arms with an intervening bight moving constantly relative to the slide during operation of the loom, said arms having 65 notches for engaging the detector tail piece

at different levels incidental to positioning of the latter occasioned by absence of the filling, or by presence of abnormal obstructions other than the filling, to effect automatic stoppage of the loom. 70

3. A filling stop motion for looms, comprising a normally stationary slide operatively connected to the belt shipper tripping mechanism, a filling detector having depending prongs and a yoke-like tail piece 75 pivoted on the slide, and a member embodying straight and overshot arms with an intervening bight moving constantly relative to the slide during the operation of the loom, said arms affording hooks positioned 80 at different levels for engaging the tail piece of the detector when the latter assumes distinctive angular positions as occasioned by reason of absence of the filling, or by presence of abnormal obstructions other than the 85 filling, to effect automatic stoppage of the loom.

4. A filling stop motion for looms, comprising a normally stationary slide operatively connected to the belt shipper tripping mechanism, a filling detector having depending prongs and a yoke-like tail piece carried 90 by the slide, and a member reciprocating constantly relative to a slide during the operation of the loom, said member embodying a straight arm and an overshot curved arm affording hooks for engaging the tail piece of the detector when the latter assumes different angular positions as occasioned by absence of the filling, or by presence of 95 abnormal obstructions other than the filling, to effect automatic stoppage of the loom. 100

5. A pivotal member for co-operation with the filling detector of a stop motion for looms, comprising a unit embodying hooked arms one of which is directly over another, said arms being recessed to afford hooks in different planes for engaging the tail piece of the filling detector, to effect automatic stoppage of the loom, in positions assumed 105 due to absence of the filling or to the presence of abnormal obstructions other than the filling.

6. A pivotal member for co-operation with the filling detector of a stop motion for looms, comprising a unit embodying two hooked arms whereof one is straight and the other curved directly thereover with an intervening bight, said arms being recessed to afford hooks in different planes for engaging the tail piece of the filling detector, to effect 110 automatic stoppage of the loom, in positions assumed due to absence of the filling or to the presence of abnormal obstructions other than the filling. 115

In testimony whereof, I have hereunto signed my name at Millville, N. J., this 12 day of October, 1925.

DAVID E. SKEDGELL.
